[57] **CLAIM**

The ornamental design for an extended headrail, as shown and described.

DESCRIPTION

FIG. 1 is a fragmentary perspective view of an ex-

tended headrail showing a first embodiment of our new design;

FIG. 2 is a fragmentary front view thereof;

FIG. 3 is a right side view thereof;

FIG. 4 is a fragmentary top plan view thereof;

FIG. 5 is a fragmentary rear view thereof; and

FIG. 6 is a fragmentary bottom plan view thereof;

FIG. 7 is a fragmentary perspective view of an ex- tended headrail showing a second embodiment of our new design;

FIG. 8 is a fragmentary front view thereof;

FIG. 9 is a right side view thereof;

FIG. 10 is a fragmentary top plan view thereof;

FIG. 11 is a fragmentary rear view thereof;

FIG. 12 is a fragmentary bottom plan view thereof;

FIG. 13 is a fragmentary perspective view of an ex- tended headrail showing a third embodiment of our new design;

FIG. 14 is a fragmentary front view thereof;

FIG. 15 is a right side view thereof;

FIG. 16 is a fragmentary top plan view thereof;

FIG. 17 is a fragmentary rear view thereof;

FIG. 18 is a fragmentary bottom plan view thereof;

FIG. 19 is a fragmentary perspective view of an ex- tended headrail showing a fourth embodiment of our new design;

FIG. 20 is a fragmentary front view thereof;

FIG. 21 is a right side view thereof;

FIG. 22 is a fragmentary top plan view thereof;

FIG. 23 is a fragmentary rear view thereof;

FIG. 24 is a fragmentary bottom plan view thereof;

FIG. 25 is a fragmentary perspective view of an ex- tended headrail showing a fifth embodiment of our new design;

FIG. 26 is a fragmentary front view thereof;

FIG. 27 is a right side view thereof;

FIG. 28 is a fragmentary top plan view thereof;

FIG. 29 is a fragmentary rear view thereof;

FIG. 30 is a fragmentary bottom plan view thereof;

FIG. 31 is a fragmentary perspective view of an ex- tended headrail showing a sixth embodiment of our new design;

FIG. 32 is a fragmentary front view thereof;

FIG. 33 is a right side view thereof;

FIG. 34 is a fragmentary top plan view thereof;

FIG. 35 is a fragmentary rear view thereof; and,

FIG. 36 is a fragmentary bottom plan view thereof.
